UNITED STATES PATENT OFFICE.

JOHN E. HILL, OF ST. LOUIS, MISSOURI, ASSIGNOR TO THE AMERICAN ROLL PAPER COMPANY, OF SAME PLACE.

PAPER-CUTTER.

SPECIFICATION forming part of Letters Patent No. 643,374, dated February 13, 1900.

Application filed June 19, 1899. Serial No. 721,010. (No model.)

To all whom it may concern:

Be it known that I, JOHN E. HILL, a subject of the Queen of Great Britain, and a resident of the city of St. Louis, in the State of Missouri, have invented certain new and useful Improvements in Paper-Cutters, of which the following is a full, clear, and exact description, reference being had to the accompanying drawings, forming part of this specification.

My invention relates to an improved manner of attaching the blade to the arms that carry it, the manner of attachment being inexpensive and of a character that will give additional strength and stiffness to the blade.

My invention consists in features of novelty hereinafter fully described, and pointed out in the claim.

Figure I is a front view of a roll-paper holder and cutter with the blade attached in accordance with my invention. Fig. II is a detached view of the blade and its arms, the former being shown mostly in section. Fig.

III is a section taken on line III III, Fig. II. 25 1 represents the arms, and 2 the blade, of a roll-paper holder and cutter. The arms are preferably made of a single piece of wire, the ends 3 of which are intended to be attached

to the top piece of the frame of the machine, and around these ends the usual springs 4 are wound. The blade is perforated at 5 for the passage of the arms, and the upper edge of the blade is bent around the connecting horizontal part 6 of the arms, as shown in Fig. III, thereby connecting the blade securely to the arms, while the connecting part 6 of the arms adds strength and stiffness to the blades. By passing the arms through perforations in the blade they act to keep the blade from rotating and the friction between the parts does not have to be depended upon, as would be the case if the arms were outside of the ends of the blade and the latter bent around the part connecting the arms.

I claim as my invention—

In a paper-cutter, the combination of supporting-arms having a connecting portion, and a blade perforated to receive the arms and having its upper portion bent around the connecting portion of the arms, substantially as set forth.

JOHN E. HILL.

In presence of—

E. S. KNIGHT,
N. V. ALEXANDER.
